UNITED STATES PATENT OFFICE

EDWARD N. JACOBI, OF MILWAUKEE, WISCONSIN, ASSIGNEE TO BRIGGS & STRATTON CORPORATION, OF MILWAUKEE, WISCONSIN, A CORPORATION OF DELAWARE

LOCK

Application filed December 19, 1928. Serial No. 326,934.

This invention relates to certain new and useful improvements in locks and has as one of its objects the provision of means for rendering its defeat by picking more difficult.

Another object of this invention resides in the provision of a lock in which means are provided to necessitate movement of the lock cylinder longitudinally before it can be turned.

Another object of this invention resides in the provision of a lock having a key controlled lock cylinder provided with a plurality of locking tumblers, one of which functions as a stop to prevent actuation of the lock cylinder until the same has been longitudinally moved a predetermined distance.

And a more specific object of this invention resides in the provision of a lock of the character described having a key controlled lock cylinder provided with a plurality of locking tumblers and rotatable in a mounting member one of the locking tumblers being longer than the others to provide a stop which prevents actuation of the lock cylinder until the same has been moved longitudinally.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a transverse, sectional view, through a lock embodying my invention with parts thereof in elevation;

Figure 2 is a view similar to Figure 1 illustrating the lock cylinder as having been moved longitudinally and partially turned a predetermined distance, said view being taken through Figure 3 on the plane of the line 2-2;

Figure 3 is a cross sectional view taken through Figure 2 on the plane of the line 3-3 with parts in elevation;

Figure 4 is a view of the end of the lock barrel prior to its assembly with the lock cylinder and illustrating the several bores therein;

Figure 5 is a perspective view of the end washer, and

Figure 6 is an elevational view of the spring which restrains longitudinal movement of the lock cylinder.

Referring now more particularly to the accompanying drawing, in which like numerals designate like parts throughout the several views, 5 represents the body or mounting member of a lock embodying my invention which has a central bore 6 to receive a lock cylinder 7. The bore 6 is provided with a pair of diametrically opposed, longitudinal channels 8 and 9 which receive the ends of a plurality of tumblers 10 to lock the cylinder against rotation in the conventional manner, the insertion of a proper key 11 retracting the tumblers into the cylinder to permit its actuation.

A second pair of diametrically opposed longitudinal channels 12 are also formed in the bore 6 to permit the insertion of a cap member 13 in the bore from its rear and which extends outwardly through a reduced bore 14 in the front face of the barrel. Outward movement therethrough is prevented by turned over ends or lugs 15 formed on the cap which engage the shoulder formed by the reduced bore 14, the lugs 15 being received in the slots 8, 9 and 12 as the cap is inserted in the barrel. The cap member 13 is adapted to receive the reduced forward end of the lock cylinder 7 which is provided with recesses 16 to receive the lugs 15 to thus maintain the same against rotation relatively to the cap.

The rear-most tumbler 17 is longer than the others so that when the key 11 is inserted its outer end 18 projects beyond the periphery of the lock cylinder remaining within the channel 8 to prevent the rotation of the cylinder, which may be effected only by longitudinally moving the cylinder towards the rear

to move the projecting end 18 of the tumbler 17 out of the channel 8 and permit rotation of the cylinder in a manner now about to be described.

- 5 The rear end of the bore 6 is provided with a pair of counterbores 20 and 19 to receive a spring 21 and a washer 22, respectively. The spring 21 is received in the counterbore 19 which is the smaller of the two and is confined between a shoulder 23 formed by reducing the diameter of the adjacent portion of the lock cylinder, and the washer 22 which is disposed within the larger counterbore 20. The washer 22 engages the shoulder formed 10 between the counterbores 19 and 20 and is there retained by spinning over the outermost end of the barrel 5, as at 24.

In order to provide the necessary enlarged 20 annular channel or space into which the projecting end 18 of the tumbler 17 may be moved by longitudinally shifting the lock cylinder, to permit rotation thereof, half of the rear end of the barrel 5 is milled to the desired depth. This produces an eccentric 25 bore 25 which extends through substantially one half of the circumference of the barrel and whose periphery is tangent with the counterbore 20 at its medial point. This method of providing the desired enlarged 30 bore throughout but half of the circumference of the barrel is utilized when the barrel is machined but when die cast it will be readily apparent that it will be unnecessary to form an eccentric bore, as half of the counterbore 19 can be increased to the desired 35 depth. This of course is impossible where machining is resorted to.

An actuator cam 26 is connected in any 40 suitable manner with the rear-most end of the lock cylinder to impart movement to any desired mechanism, not shown, upon rotation of the lock cylinder.

From the foregoing description, taken in 45 connection with the accompanying drawing, it will be readily apparent to those skilled in the art to which an invention of this character appertains, that I provide an improved lock construction which is so constructed that picking thereof is rendered considerably more 50 difficult due to the fact that the lock cylinder must be moved longitudinally before rotation can be effected.

What I claim as my invention is:

1. In a lock of the character described including a barrel, a lock cylinder rotatable therein, said lock cylinder having a plurality of tumblers retractible upon the insertion of a proper key, one of said tumblers being longer than the others to at all times have a part disposed outwardly of the periphery of the lock cylinder to restrict rotation of the cylinder, and means into which the projecting end of said tumbler may be moved to permit rotation of the cylinder.
- 60 2. In a lock of the character described in-

cluding a barrel having a lock cylinder rotatable therein, said cylinder having a plurality of tumblers retractible by the insertion of a proper key, one of said tumblers being of greater length than the others to have a portion at all times disposed beyond the periphery of the lock cylinder to normally prevent rotation thereof, and means whereby longitudinal movement of the lock cylinder a predetermined distance moves the extended end of said tumbler into a channel to permit rotation of the cylinder in one direction.

3. In a lock of the character described including a barrel having a lock cylinder rotatable therein, said cylinder having a plurality of tumblers retractible by the insertion of a proper key, one of said tumblers being of greater length than the other to have a portion at all times disposed beyond the periphery of the lock cylinder and normally prevent rotation thereof, means whereby longitudinal movement of the lock cylinder a predetermined distance moves the extended end of said tumbler into a channel to permit rotation of the cylinder in one direction, and means yieldably urging the lock cylinder against such longitudinal movement.

4. In a lock structure of the character described, a bored mounting member, a lock cylinder rotatable and longitudinally shiftable within the bore of the mounting member, yieldable means normally restraining longitudinal shifting of the lock cylinder, a plurality of locking tumblers carried by the lock cylinder and engageable with an abutment carried by the mounting member in communication with its bore, said locking tumblers being retractible upon the insertion of a proper key, and one of the tumblers being of greater length than the others whereby a portion thereof remains in engagement with the mounting member carried abutment after the insertion of the key, and said tumbler being disengageable from the mounting member carried abutment by longitudinal shifting of the lock cylinder.

5. In a lock structure of the character described, a bored mounting member, a lock cylinder rotatable and longitudinally shiftable therein, stop means at the forward end of the mounting member for preventing outward movement of the lock cylinder, means for closing the inner end of the mounting member, spring means confined between the means closing the inner end of the mounting member and the lock cylinder normally yieldably urging the cylinder into engagement with the stop means at the forward end of the mounting member, a plurality of locking tumblers carried by the lock cylinder normally yieldably engaged with an abutment carried by the mounting member in communication with its bore to releasably secure the lock cylinder against rotation,

said tumblers being retractile upon the insertion of a proper key, one of the tumblers being of greater length than the others whereby a portion thereof remains in engagement with the mounting member carried abutment after the insertion of the key, and said mounting member having a channel communicating with the abutment and normally disaligned with the locking tumbler of greater length into which the said locking tumbler may be moved to free the cylinder for rotation upon longitudinal shifting of the lock cylinder inwardly with respect to the mounting member.

6. In a lock structure of the character described, a mounting member having an abutment, a lock cylinder rotatable and longitudinally shiftable therein, a plurality of locking tumblers carried by the lock cylinder and normally yieldably engaged with the mounting member abutment to restrain rotation of the lock cylinder, said locking tumblers being retractile by the insertion of a proper key, and means whereby the lock cylinder is held against rotation after the tumblers have been retracted until the cylinder is shifted longitudinally inwardly a predetermined degree, said lock cylinder being longitudinally shiftable independently of the key.

7. In a lock of the character described, including a mounting member, a lock cylinder having a key slot, a plurality of locking tumblers carried by the lock cylinder, said lock cylinder being movable in one direction angular to the first mentioned direction independently of a key and being movable in another direction in the performance of its locking function upon the retraction of the locking tumblers by the insertion of a proper key, and means whereby one of said tumblers provides a stop to restrain actuation of the lock cylinder in the performance of its locking function until movement of the cylinder has been effected in said first mentioned direction.

8. In a lock of the character described, including a mounting member, a lock cylinder having a key slot, a plurality of locking tumblers carried by the lock cylinder and normally restraining rotation of the lock cylinder, said lock cylinder being rotatable upon the retraction of the locking tumblers by the insertion of a proper key and being longitudinally shiftable independently of the key, and means whereby one of said tumblers provides a stop to restrain rotation of the lock cylinder until longitudinal movement thereof has been effected.

60 9. In a lock of the character described, including a mounting member, a lock cylinder having a key slot, a plurality of locking tumblers carried by the lock cylinder for releasably securing the lock cylinder against rotation, said lock cylinder being rotatable

upon the retraction of the locking tumblers by the insertion of a proper key and being longitudinally shiftable independently of the key, means yieldably holding the lock cylinder against longitudinal shifting, and means 70 for holding the lock cylinder against rotation until it is shifted longitudinally a predetermined distance.

10. In a lock structure of the character described, a bored mounting member having an 75 annular abutment adjacent one end, a lock cylinder having a key slot and mounted within the mounting member bore, a plurality of locking tumblers carried by the lock cylinder and engageable with a longitudinal abutment carried by the mounting member in communication with its bore to normally releasably secure the lock cylinder against rotation, said tumblers being retractile by the insertion of a proper key and the lock cylinder 85 being longitudinally movable in the mounting member bore independently of the key, means normally yieldably urging the lock cylinder longitudinally into engagement with the mounting member annular abutment, and 90 means carried by the lock cylinder and engaging the longitudinal abutment in the mounting member to prevent rotation of the lock cylinder until the cylinder has been shifted longitudinally away from the annular abutment and against its urging means. 95

11. In a lock structure of the character described, a mounting member, a lock cylinder having a key slot and mounted within the mounting member, locking tumblers carried 100 by the lock cylinder and engageable with the mounting member to normally releasably secure the lock cylinder against rotation, said locking tumblers being retractile by the insertion of a proper key in the slot and the 105 lock cylinder being longitudinally shiftable independently of the key, and means whereby longitudinal shifting of the lock cylinder is required in addition to the insertion of the proper key to free the lock cylinder for rotation. 110

In testimony whereof I have hereunto affixed my signature.

EDWARD N. JACOBI.

CERTIFICATE OF CORRECTION.

Patent No. 1,869,426.

August 2, 1932.

EDWARD N. JACOBI.

It is hereby certified that error appears in the printed specification of the above numbered patent requiring correction as follows: Page 3, lines 35 and 36, claim 7, strike out the words "angular to the first mentioned direction" and insert the same to follow the word "direction" in line 38, of same claim; and that the said Letters Patent should be read with this correction therein that the same may conform to the record of the case in the Patent Office.

Signed and sealed this 22nd day of November, A. D. 1932.

M. J. Moore,
Acting Commissioner of Patents.
